[57] CLAIM

The ornamental design for container for odorant, as shown and described.

DESCRIPTION

FIG. 1 is a perspective view of my container for odorant showing my new design;

FIG. 2 is a bottom view thereof;

FIG. 3 is a right side view thereof, the opposite side view being a mirror image;

FIG. 4 is a front view thereof;

FIG. 5 is the rear view thereof;

FIG. 6 is a top view thereof; and,

FIG. 7 is a cross-sectional view along line 7 of FIG. 2.

FIG. 1.

FIG. 2.

FIG. 2.

FIG. 3.

FIG. 4.

FIG. 5.

FIG. 6.
